George Garst,
BY

Geo. P. Kimmel. ATTORNEY.

UNITED STATES PATENT OFFICE.

JOHN J. BERSCHEID, OF CHAMPAIGN, AND GEORGE GARST, OF URBANA, ILLINOIS.

CORNER-BEAD ERECTOR.

Application filed March 18, 1926, Serial No. 95,740. Renewed April 23, 1927.

This invention relates to leveling devices and pertains particularly to such an instrument designed to be used in connection with the setting up of corner bead strips.

5 The invention has for its primary object the provision, in a manner as hereinafter set forth, of a level structure having means for supporting a corner bead strip so that the strip may be placed in true position at a wall corner and so held until nailed into place.

10 As is well known, in the construction of buildings in which plastered walls are used, the projecting corners of the walls are usually protected by the application thereto of a substantially V-shaped metal strip, the corner formed along the joining edges of the sides thereof being extended to provide a bead portion. This strip after being placed in position over a corner, has the plaster of the wall placed thereover leaving only the outer edge of the bead portion along the angle thereof exposed to receive any knocks which would otherwise be received by the plaster if the strip was not used. The placing and securing into position of these strips in a perfectly vertical position is rather difficult unless some truing up instrument is used in connection therewith.

15 The device embodying this invention is designed to hold the strips in true position while they are being secured in place.

A further and final object of the invention is the provision, in a manner as herein-after set forth, of a corner bead strip holding and leveling device of strong and durable construction, easy to use and inexpensive to manufacture.

20 The invention will be best understood from a consideration of the following detailed description taken in connection with the accompanying drawings forming a part of this specification, with the understanding that the invention is not confined to any strict conformity with the showing of the drawings but may be changed and modified so long as such changes and modifications mark no material departure from the salient features of the invention as expressed in the appended claims.

25 In the drawings:—

Figure 1 shows the device embodying this invention, in perspective view and as in use.

Figure 2 is a transverse section through the device and through the corner of the wall structure to which it is applied.

Figure 3 shows the device in side elevation, and

Figure 4 shows a front elevation of the same.

Referring now to the drawings in detail wherein like numerals of reference indicate corresponding parts throughout the several views, there is indicated generally by the numeral 1 the device embodying this invention. A corner wall studding is indicated at 2 and to the outer faces of this studding there are secured the lath members 3 which are applied preparatory to plastering. As shown in Figure 2 these lath members 3 do not overlap at the outer corner of the studding 2 thus giving a square effect to the corner.

25 The instrument 1 is substantially T-shaped in cross section as shown in Figure 2 and constitutes a relatively long head body 4 from the central longitudinal face of one side of which there extends at right angles the body 5. The central portion of the head 4 is slightly enlarged as shown in the figures and secured to the outer face of this enlarged portion is a circular plate 6 having a central aperture therethrough and carrying a spirit tube 7 which extends across the aperture. The plate is adjustably secured to the face of the head 4 by means of the screw members 8 and is provided with 30 the short circumferentially extending slots 9 through which the securing screws 8 pass and by means of which the plate can be shifted to change the relation between the spirit level and the head 4. As is shown the 35 spirit level is here secured transversely of the head. A socket or recess 10 is formed in the head behind the spirit level, as shown.

The free front edge of the body portion 5 is provided throughout with a substantially V-shaped channel 11, at the inner part or apex of which there is formed the relatively narrow groove 12. The body is provided, near its front edge, with the transversely extending apertures 13 which open 40 through the walls of the channel 11 and adapted to be extended through each of these apertures or passages, is a pin member 14 secured, by means of the chain or flexible element 15, to the side of the body 5, by 45 means of the eye 16.

Secured to one side of the head 5 over the recess 17 formed through the head, is the plate 18 through which a central aperture is formed over which central aperture the 50

spirit level 19 is mounted, being secured at its ends to the plate 18.

When using this device the metal corner bead strip which is usually formed of sheet metal and which is of the same transverse configuration as the channel and groove 11 and 12 in the body 5, is placed in this channel and groove in the manner shown in Figure 2. The instrument is adjusted upon the 10 bead strip to align the apertures 13 with the nail holes formed through the strip and thereupon the retaining pins 14 are extended through the apertures and the nail holes in the strip, thus securing the strip to the instrument. The strip 20 is then placed in 15 position along the edge of the wall over the ends of the laths 3 as is shown, the square corner effect resulting from not overlapping the ends of the laths 3 allowing space for the pins 14 to extend across the corner of the wall as shown. When the strip is level, as 20 indicated by the spirit levels 7 and 19, the upper and lower ends are nailed in position and thereafter the pins 14 may be withdrawn and the instrument removed so that 25 the strip can be further securely nailed to the corner of the wall structure.

From the foregoing description it will be readily seen that the device embodying this 30 invention will enable a builder to easily and quickly place into position the corner bead strip and at the same time get the same properly aligned so that the corner of the finished wall will be perfectly vertical.

Having thus described our invention what 35 we claim is:—

1. In a device of the character described, an elongated body member having a substantially V-shaped channel extending throughout one edge thereof to receive a corner bead strip, said body further having a groove formed therein at the crotch of said channel to receive a portion of said strip, and means carried by the body for holding the strip in

the channel while being placed in position. 45

2. In a device of the character described, an elongated body member having a substantially V-shaped channel extending throughout one edge thereof to receive a corner bead strip, said body further having a groove formed therein at the crotch of said channel to receive a portion of said strip, and securing members adapted to be extended through apertures in the walls and transversely of, said channel, through nail 50 apertures in said bead, to hold the bead in position while being set to a wall corner. 55

3. In a device of the character described, an elongated member substantially T-shaped in cross section having the single free edge of the body thereof provided with a substantially V-shaped channel having a groove at the crotch thereof, to receive a correspondingly shaped corner bead strip, securing pins adapted to hold said bead in said channel, and a leveling device carried upon the head of the member for setting the bead in proper position. 60

4. In a device of the character described, an elongated body substantially T-shaped in cross section having the single free edge of the body provided with a longitudinally extending V-shaped channel to receive a wall corner strip, and a groove formed along the crotch of said channel to receive a corresponding portion of said strip, said body further having a series of transversely arranged passages formed therethrough and through the walls of said channel, pin members designed to be projected through said 70 passages to extend transversely of said channel through apertures in the strip, and flexible elements securing said pins to the body. 75

In testimony whereof, we affix our signatures hereto.

JOHN J. BERSCHEID.
GEORGE GARST.
